UNITED STATES PATENT OFFICE.

EDWARD D. HOUSTON, OF WORCESTER, MASSACHUSETTS.

SAFETY-PIN.

1,192,898.

Specification of Letters Patent.

Patented Aug. 1, 1916.

Application filed February 6, 1915. Serial No. 6,594.

To all whom it may concern:

Be it known that I, EDWARD D. HOUSTON, a citizen of the United States, residing at Worcester, in the county of Worcester and 5 State of Massachusetts, have invented a new and useful Safety-Pin, of which the following is a specification.

This invention relates to a safety pin, preferably formed entirely of wire, but at 10 any rate, having a pin proper integral with a length of wire which constitutes the back of the pin.

The principal objects of the invention are to provide a construction of this type in 15 which the whole device, if desired, can be made of a single piece of continuous wire, and in which the pin itself shall be provided with a simple means at its end adapted to be conveniently grasped, and suitable 20 for manipulating the pin so that the pin can be operated and guided effectively by grasping it; to provide a construction in which the body of the pin passes over the pin member itself so as to furnish bearing points on 25 both sides of the pin, preferably substantially in the same plane, for engaging the material in which the pin is placed and holding the back flat thereon; to provide, in addition to the latter feature, a second crossing member over to the first side of the pin 30 whereby three points are secured practically in the same plane to prevent turning of the pin after once being put in position; to provide means by which the shape of the pin 35 itself can be made ornamental or an ornament attached to the pin; to provide an integral coil, preferably on the end of the back, constituting a retainer for the point of the pin; and especially to provide a back 40 of yielding construction and such form that it will yield lengthwise to permit the point of the pin to be drawn from the retainer simply by pulling on it, and will also permit the pin to be introduced into the retainer in a simple manner.

Reference is to be had to the accompanying drawings in which,

Figure 1 is a plan of a pin constructed in accordance with this invention and showing 50 it in position in a piece of cloth; Fig. 2 is a similar view showing how the pin can be attached and released from the cloth merely by a longitudinal pull; Fig. 3 is a perspective view of the end of the pin; Fig. 4 is a 55 plan of a pin also constructed in accordance

with this invention and showing some modifications, and Fig. 5 is a similar view of another modified form.

Referring first to the form shown in Figs. 1, 2 and 3, it will be seen that the pin, in 60 this form, consists of a single integral continuous length of wire. One end of the wire is formed into a straight shaft 10 which constitutes the pin member or pin proper. This is bent in its plane to form a scroll 11 which 65 in this instance passes directly under the butt end of the pin and then is bent clear around this to form a second scroll 12. These two scroll members are in the same plane and the first mentioned one is substantially 70 rigid with respect to the pin on account of its contact with the wire underneath. This scroll member 11 being flat and rigidly connected with the pin, can be grasped rigidly between the finger and 75 thumb and used for guiding and manipulating the pin point either with or without the assistance of the other scroll member 12. It is to be observed that the scroll 12 is provided with a bend 13 and then continued inwardly to form a bar 14 crossing over the pin 10. This bar is shown in this case as having a coil 15 at its end substantially in 80 the plane of the bend 13 and located substantially at the same distance from the pin 85 member 10, but of course on the opposite side. From the coil the wire is bent in the opposite direction to form a second bar 16 which also passes over the pin member 10 and terminates in a bend at 17 which lies in 90 the plane of the coil 15. In practice, these three points, 13, 15 and 17, lie on the surface of the cloth or other material in which the pin is placed and serve to hold the pin in a flat position thereon, preventing its 95 turning about the pin member as a center. The wire is shown as formed with a small conical coil 18 at the end integral with the rest of the wire and serving as a retainer for the pin point.

In the manipulation of the device the coils 11 and 12 are grasped between the thumb and finger and then the pin point is directly within the control of the user. It can be manipulated and guided in any desired way 105 and forced into the fabric at the desired point. When this is done and it projects beyond the fabric, the user, then still having hold of the flat members 11 and 12, forces the point of the pin against the slanting 110

surface 19 between the bend 17 and the coil 18 and this guides the point of the pin down into the retaining coil. When it is desired to withdraw the pin, it is not necessary to grasp the retaining coil at all, or to guide the pin in any way. It is simply pulled directly out, as shown in Fig. 2. The retaining coil then engages the cloth and is held back, or this action stretches out the back of the pin which consists of the parts 13 and 16 and allows the pin point to escape from the retainer. The set of the wire is such that the pin point will spring away from the retainer when released. Thus, considerable saving is secured in the time required for withdrawing the pin and there is no danger of its getting caught so that it cannot easily be detached. Nevertheless, there is no danger of its being detached accidentally.

By having the three-point bearing on the pin so that it engages the cloth at three points substantially in the same plane and on both sides of the pin itself, the pin will always stay in the place in which it is put and cannot turn up at right-angles from that position, as is the case with ordinary safety pins. Furthermore, an ornament, as for example a stone 20, can be applied to the pin as shown in Fig. 1, in a very convenient manner; and either with or without an ornament, the pin is of an attractive appearance and can be worn in a scarf or in any position in which it is visible without presenting in any way an unsightly appearance. The pin can be manufactured at a small expense and is useful, both for ornamental purposes and as a true safety pin. It is to be noted, also, that the surface 19 extends downwardly under the pin point and forms a guard beyond which the pin point cannot move in that direction, besides forming a guide for guiding the pin point into the retainer. In the form shown in Fig. 4, most of these advantages are also retained. In this case the pin member 10^a is provided with a scroll in the form of a loop 11^a which has a portion of the functions of the scroll, but it is not so intimately connected with the main pin member 10^a. It forms a bearing point however on one side of the pin. From this an arm 12^a extends directly to form a bearing point 13^a on the other side of the pin member and in the plane thereof, and a bar 14^a, which constitutes the back of the pin, extends over the pin member to form the bend 17^a on the other side and in the same plane as the first named bends. It will be seen therefore that some of the bearing points can be obtained without reference to the back of the pin. This pin is provided with a retainer 18^a of a different shape from that shown in the first two figures, but performs similar functions. A guiding surface 19^a for the pin

point also constituting a guard is shown. In this case it has a wire 21^a which forms an additional guard.

In Fig. 5 another form is shown in which the pin member 10^b is provided with a curve or scroll 11^b that is twisted around the base of the pin to form coils 22^b which firmly secure this flat member or scroll 11^b to the pin and consequently furnish a still more secure and firm handle for manipulating the pin. In this case the scroll 11^b forms a bearing at 13^b on one side of the pin member and a bearing 15^b is formed on the other side in the same plane. A bar 16^b extends from this point over the pin to form the back of the pin and provide a third bearing point 17^b on the other side. In this case a retainer 18^b is also shown. Most of the advantages mentioned in describing the first form shown are also present in the last two forms.

Although I have illustrated and described only three forms of the invention, I am aware of the fact that modifications can be made in them, that features shown in one can be applied to others, and that other changes can be made in form and material without departing from the scope of the invention as expressed in the claims. Therefore, I do not wish to be limited to the details of construction herein shown, and described, but

What I do claim is:—

1. As an article of manufacture, a safety pin comprising a pin member, a back crossing the pin member at a point between its ends and yieldingly connected therewith, and a retainer for the pin point on the end of said back which the pin is adapted to enter lengthwise, a portion of said back constituting a guard within reach of the pin point for guiding the pin point into the retainer and preventing the pin point passing far to one side thereof.

2. As an article of manufacture, a safety pin comprising a pin member having at the butt thereof an integral continuous plane bend of wire arranged transverse thereof but in the plane of the pin member by which the pin member can be operated, the end of said bend crossing the pin at a short distance from its end to give it rigidity and extending beyond the pin on the other side and then back again to the first side.

3. As an article of manufacture, a safety pin having a pin member provided at the butt thereof with a transverse bend crossing the pin to render it rigid by which the pin member can be directly manipulated, and having a body extending across the pin member again to the same side and provided at the end with a catch or guard for the point of the pin member.

4. As an article of manufacture, a safety pin comprising a pin member having at the

butt thereof an integral continuous plane bend of wire arranged to cross the pin member but in the plane of the pin member by which the pin member can be operated, said 5 bend having a continuation thereof constituting the body of the pin and extending across the pin member a second time and having at its opposite end an integral coil constituting a catch or guard for receiving 10 the point of the pin member.

5. As an article of manufacture, a safety pin comprising a pin member provided at the butt end thereof with a single flat transverse coil with which the base of the pin 15 member is fixedly connected, the pin crossing this coil in contact therewith whereby this coil constitutes means for operating the pin member, said coil having an extension passing over the pin member to a point on 20 the other side which lies substantially in the same plane as the plane of said coil and provided with means on the end for retaining the point of the pin member.

6. As an article of manufacture, a safety 25 pin comprising a pin member provided at the butt end thereof with a flat transverse coil with which the pin member is fixedly connected, said coil having a bend provided with an extension passing over the body of 30 the pin to a point on the other side which lies substantially in the plane of said bend, and then extending back again over the pin member to a point on the opposite side, and provided with means on the end for retaining 35 the point of the pin member.

7. As an article of manufacture, a safety 40 pin consisting of a single continuous length of wire, one end of which constitutes a pin member, a scroll formed at the butt of said pin member, passing by it and in contact 45 with it, and then out and around the scroll in the plane thereof to form a plane member by which the pin can be manipulated, and then being carried over the pin to the opposite side thereof, and finally back again over 50 the pin to the first side and having a coil on the end for retaining the end of the pin.

8. As an article of manufacture, a safety 55 pin comprising a pin member and having a body connected with said pin member at the butt thereof and projecting to one side thereof in the plane of the pin member, then crossing over the pin member to a point on the other side substantially in the same 60 plane close to the butt thereof, and then

again crossing the pin to the first named side to a point also substantially in the same plane and about at the center of the pin and body, to form three bearing points on opposite sides of the pin and at a distance 65 therefrom substantially in the same plane for engaging the material on which the pin is used and preventing said body from turning thereon, the second of said points being located substantially midway between the first and third.

9. As an article of manufacture, a safety pin comprising a pin member and having a body connected with said pin member at the butt thereof and projecting to one side 70 thereof in the plane of the pin member, then crossing over the pin member to a point on the other side substantially in the same plane, to form bearing points on opposite sides of the pin and at a distance therefrom 75 substantially in the same plane for engaging the material on which the pin is used and preventing said body from turning thereon, said body being of spring wire, and having a retainer for the pin point at the 80 end beyond the last bearing point, whereby upon pulling the pin member back longitudinally the pin point can be drawn out of the retainer.

10. As an article of manufacture, a safety 85 pin comprising a pin member and having a body connected with said pin member at the butt thereof and projecting to one side thereof in the plane of the pin member, then crossing over the pin member to a 90 point on the other side substantially in the same plane, and then again crossing the pin to the first named side to a point also substantially in the same plane, to form three bearing points on opposite sides of the pin 95 and at a distance therefrom substantially in the same plane for engaging the material on which the pin is used and preventing said body from turning thereon, said body being of spring wire, and having a retainer 100 for the pin point at the end beyond all of said bearing points, whereby upon pulling the pin member back longitudinally the pin point can be drawn out of the retainer.

In testimony I have hereunto set my hand, 105 in the presence of two subscribing witnesses.
